COVER FOR A GARDEN HOSE NOZZLE

Steve Falcetti, Forest Hills, N. Y.

Application September 25, 1957, Serial No. 47,861

Term of patent 3½ years

(Cl. D91—1)

FIG. 1.

FIG. 2.

FIG. 3.

Fig. 2 is a top plan view of the cover, and

Fig. 3 is a front elevational view of the cover.

I claim:

The ornamental design for a cover for a garden hose nozzle, substantially as shown.
